UNITED STATES PATENT OFFICE.

ALBERT G. SMALLEY, OF CHELSEA, MASSACHUSETTS.

DESIGN FOR A FRUIT-JAR.

SPECIFICATION forming part of Design No. 25,354, dated April 7, 1896.

Application filed February 24, 1896. Serial No. 581,862. Term of patent 14 years.

To all whom it may concern:

Be it known that I, ALBERT G. SMALLEY, of Chelsea, in the county of Suffolk and State of Massachusetts, have invented a new Design 5 for a Fruit-Jar, of which the following is a specification.

Referring to the accompanying drawings, Figure 1 is a top plan; Fig. 2, a bottom plan and Fig. 3 a vertical section at line 3 3 of Fig. 10 1; Fig. 4, a vertical section at line 4 4 of Fig. 1; and Fig. 5, a horizontal section at line 5 5 of Fig. 3.

The figures are deemed necessary to fully illustrate my new design.

15 The leading feature of my design consists in a squat, wide and short necked jar, which is squarish in cross-section and has a flattened annular shoulder at the base of the neck and rounded horizontal and vertical 20 corners, including rounded surfaces, at each junction of a top or bottom forming wall with a side wall of the jar, three of the sides of the jar being slightly curved outwardly and the fourth side wall flattish.

25 A is the jar, and a its wide and short neck.

At the base of neck a is the flat shoulder a' , which curves downwardly into the four side walls a^2 , a^3 , a^4 , and a^5 , forming the rounded upper horizontal corners a^6 , a^7 , a^8 , and a^9 , and also rounded portions a^{10} at the four junctures of the bottom and side walls of the jar. Side walls a^2 , a^3 , and a^4 are outwardly curved laterally, and side a^5 is flattish, the cross-sectional form of the body of the jar being squarish. The vertical corners a^{11} are rounded, 35 and the horizontal corners a^{12} are rounded, together with the four junctures of the side walls with the bottom a^{13} .

What I claim is—

The design for a fruit-jar herein shown and 40 described.

In testimony whereof I have signed my name to this specification, in the presence of two subscribing witnesses, on this 4th day of February, A. D. 1896.

ALBERT G. SMALLEY.

Witnesses:

EDWARD S. BEACH,
E. A. ALLEN.
